UNITED STATES PATENT OFFICE.

WILLIAM D. PIERSON, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

MEANS FOR CONTROLLING ASSOCIATED MECHANISMS OF WIRE-DRAWING MACHINERY OR THE LIKE.

Application filed May 21, 1921. Serial No. 471,407.

To all whom it may concern:

Be it known that I, WILLIAM D. PIERSON, a citizen of the United States, residing at Waterbury, in the county of New Haven and 5 State of Connecticut, have invented certain new and useful Improvements in Means for Controlling Associated Mechanisms of Wire-Drawing Machinery or the like, of which the following is a specification, reference 10 being had therein to the accompanying drawings.

My invention relates to means for controlling associated mechanisms of wire drawing machinery or the like, referring more particularly to such mechanisms forming part 15 of wire drawing machinery wherein there are wire drawing drums and a wire drawing or finishing block.

It is the object of this invention, among 20 other things, to provide simple, economical and effective means for stopping at one time all of the wire drums and the finishing block of such wire drawing machines, starting the drawing drums and finishing block 25 independently, and starting and stopping the finishing block independently of the drawing drums.

To these, and other ends, my invention 30 consists in the means for controlling associated mechanisms, having certain details of construction and combinations of parts, as will be hereinafter described and more particularly pointed out in the claims.

Referring to the drawings, in which like 35 numerals of reference designate like parts in the several figures;

Figure 1 is an elevation of a wire drawing machine having my improvements connected therewith;

40 Figure 2 is an enlarged partial end view thereof, the parts in section being taken generally upon line 2—2 of Figure 1;

Figure 3 is a detailed elevation of the 45 treadle mechanism for the wire drawing or finishing drum and adjacent parts;

Figure 4 is a sectional view of some of the parts shown in Figure 3, taken generally upon line 4—4 thereof; and

50 Figure 5 is a plan view of the extension rod, partly in section, and some adjacent parts.

I have shown herein a wire drawing machine of a well known type, and in brief it

consists essentially of a base 10, a table 11 supported thereabove by standards 12 or 55 similar means, and within which is rotatably connected the drum shafts 13, each having a wire drawing drum 14 mounted thereon. These drums are rotated from a driving shaft 15, having pinions 16 thereon that mesh into 60 the pinions 17. Substantially parallel with the drum shafts 13 is a block shaft 18 upon the upper end of which a wire drawing block 19 is suitably connected by a clutch mechanism, not shown, operated through a collar 65 20 slidably mounted upon said shaft. This clutch mechanism is of a well known type and does not herein require illustration or description. Any other form of make and break mechanism may be substituted if desired, such as a clutch on the main shaft instead of inside of the block. One form of adaptable clutch mechanism is shown in Patent No. 1,025,588 dated May 7, 1912.

The block shaft 18 is also rotated from the 75 shaft 15 through the bevel gears 21 and 22. The numeral 23 designates the main shaft or what may be properly termed the driving means which is journaled in the standards 24 and upon which is a pinion 25, the teeth of 80 which mesh into those of a gear 26 having an axis substantially parallel to the shaft 15, and connected therewith through a clutch 27 of a well known type.

The main shaft or prime mover 23 may be 85 rotated either from a motor, by a belt, train of gears, or any other suitable source of power, but is designed to be rotated continuously, while the drums 14 and block 19 are only designed to be operated as desired.

Heretofore the two clutches, that is, the one associated with the shaft 15 and the other with the block 19, have been operated without any common control. To stop the machine the operator manipulated the 95 treadle which controls the main driving clutch 27. This, of course, stopped the wire drawing drums and the wire block, inasmuch as the block is also driven from the shaft 15. Provided the operator neglected to throw off 100 the independent clutch for the wire block the result would be that upon again starting up the machine by the treadle controlling the main clutch 27, both the wire drawing drums and wire block would start simultaneously under the full load, which would 105

cause a heavy strain upon the main shaft or prime mover 23. If this latter, perchance, is driven by a motor, this strain would be very liable to blow out the fuses. Also the 5 extreme tension on the wire by the starting of the wire block 19 would have a tendency to cause it to break, in which case the broken end of the wire is whirled around by the wire block, frequently causing injury and 10 damage both to the machine and to any person who happens to be in the vicinity.

With my mechanisms such results are impossible, as I provide means whereby the main clutch 27 and the clutch operating the 15 wire block 19 are both thrown out of engagement at the same time. This results in the stopping of all of the machine parts except the main shaft or prime mover 23. In the reverse operation, that is, to start the mechanism, it is impossible to start the wire block 20 19 at the same time as the wire drawing drums 14, the latter being started first, and then by a subsequent operation the latter being set in motion.

25 The mechanism for manipulating the main clutch 27 as herein shown comprises a plurality of rock levers 23 pivotally mounted upon fixed parts by the pintles 30. These rock levers are provided with foot plates 32 and 33 upon opposite sides of the pivot mounting and downwardly depending arms 34. In the drawings two of the rock levers 28 are shown, but it is obvious that more or less may be used as desired.

30 35 The mechanism for operating the clutch for the wire drawing block is independently controlled by the rock lever 29 pivotally connected to a fixed part by the pintle 31 and having foot plates 50 and 51 thereon, a 40 downwardly projecting arm 52 and an upwardly projecting arm 42.

A rod 35 extending along the front of the machine is pivotally connected with the arms 34 and the one adjacent to the clutch 27 with the rock arm 36 by which said clutch is operated through the link 37. At the outer end of the rod 35 an extension rod 40 is connected therewith through a turn buckle 41. With this turn buckle 41 the position 50 of the extension rod 40 may be varied in relation to the rod 35, thus providing means for adjusting relatively the position of the slot 39 therein.

Attached to the rock lever 29 is a latch 55 55 pivoted at 54 to swing freely, and a spring 55 exerts its pull so as to hold the lower end of the latch in the notch 57 of the plate 56 attached to or integral with the base plate 10.

60 65 In the position shown by full lines in Figures 1 and 3, the rock lever 29 cannot be actuated by the foot plate 50, because of the position of the latch 53 relative to the plate 56.

65 As illustrated the arms 34 are integral

with the rock levers 28 and the arm 52 with the rock lever 29, but this is not essential for they may be made in two or more parts.

The collar 20 is moved along the block shaft 18 by the rock arm 42 and rock lever 70 43 connected by a turn buckle 44 which permits relative adjustment. A yoke arm 45 connected with the rock lever 43 is slotted to receive the pins 47 projecting radially from the collar 20 whereby movement of 75 the rock lever 43 imparts movement to the collar 20 along the block shaft 18. A stop 48 against which abuts the stop screw 49 in the rock lever 43 limits the movement of 80 said rock lever and through it the clutch by 85 which the wire drawing block 19 is operated.

This particular form of lever connection is desirable for use with a coil clutch, the toggle motion locking the sliding collar 20 85 in place as the screw 49 abuts against the stop 48.

Assuming that the main shaft or prime mover 23 is continually rotating and the wire drawing drums 14 and block 19 are at 90 rest, as illustrated in Figure 1, the drums are put in motion by applying pressure to the foot plate 33 upon any one of the rock levers 28, and the rod 35 and link 37 impart movement to the rock arm 36 actuating the clutch 27 so that a connection is made between the main shaft or prime mover 23 and the shaft 15, putting the latter in motion and the wire drawing drums 14 connected therewith.

During the above movement of the rod 35 and extension rod 40, however, the clutch that operates the wire block 19 is not actuated, as the pin 38 lies idle within the slot 39.

105 During the latter portion of the movement of the extension rod 40 as the main clutch 27 is placed in operation, the pin 58 adjustably secured to the extension rod within the slot 59, contacts with and moves the latch 53 out of the notch 57. Rock lever 29 being now released, the block clutch is actuated by applying pressure to the foot plate 50 and the block 19 is set in motion through the movement of the collar 20, at 110 which time the pin 38 travels through the slot 39 permissible only when the clutch 27 is in its engaged or operative position.

In stopping the machine, pressure may be applied to the pressure foot 32 of any of the 110 rock levers 28, and through the rod 35 the main clutch 27 releases its hold so as to disengage the shaft 15 from the main shaft or prime mover 23. As the extension rod 40 moves with the rod 35, the rock lever 29 125 is also actuated and the block clutch disengaged, thus all of the mechanisms are brought to a full stop at one and the same time.

130 The relative position of the rock lever 29

and adjacent parts, when the block 19 is in motion, is shown by broken lines in Figure 3.

The rock lever 29 may be moved upon its pivot mounting by pressure upon the foot plate 51 to disengage the block clutch at any time when the main clutch is engaged, during which time the pin 38 slides within the slot 39. With the rock lever 29 in the position just outlined the latch 53 is held with 10 in the notch 57 by the spring 55. The block clutch cannot therefore be again engaged for rotation of the block until the latch is released, either by the pin 58, manually, or by such other means as may seem desirable. 15 Thus it will be noted that the block clutch cannot be thrown into engagement until the drawing drums are in rotation and that after the drawing drums are in rotation, the block clutch may be thrown either into or 20 out of engagement.

When the main clutch is moved to its inoperative position, the block clutch is also synchronously released and is automatically locked. It cannot be again thrown into engagement until after the main clutch. If 25 the operator, however, desires to start the machine under a light or no load, it may be done by releasing the latch 53, thus allowing the rock lever 29 to be actuated by 30 pressure upon the foot plate 50 which throws into engagement the block clutch and at the same time moves the rod 35 to engage the main clutch.

Minor changes and alterations may be 35 made within my invention, aside from those herein suggested, and I would therefore have it understood that I do not limit myself to the exact construction herein shown and described, but claim all that falls fairly 40 within the spirit and scope of the appended claims.

What I claim as new and desire to secure by Letters Patent, is:—

1. In a wire drawing machine, the combination with a rotating drum; of a rotating block; means for independently setting in motion said drum and said wire block; and means for stopping the motion of said wire block by mechanism actuated through 50 the same means that stops the motion of said drum.

2. In a wire drawing machine, the combination with a rotating shaft; of a rotating drum; a rotating block; clutch mechanism 55 forming a make and break connection between said shaft and said block; a clutch mechanism forming a make and break connection between said shaft and driving means or other source of power; and means for 60 actuating both of said clutch mechanisms so that movement of said drum and block may be discontinued; and means for making the connection between said shaft and the clutch mechanism for said block so that said latter clutch mechanism may be actuated inde-

pendently of the former clutch mechanism for the purpose of independently starting said block in motion.

3. In a wire drawing machine, the combination with a rotating drum; of a rotating block; means for independently setting in motion said drum and said wire block through clutch mechanisms; including means for stopping the motion of said wire block by mechanism having such relation to 75 the aforesaid means that it may be actuated independently thereof.

4. In a wire drawing machine, the combination with a driving means; of a rotating shaft; a make and break connection mechanism therebetween; a rotating drum positively driven from said shaft; a wire block; a make and break connection mechanism between said wire block and said shaft; and means for actuating each of said make and 85 break connection mechanisms so that motion of said drum and block may be discontinued and permitting independent movement of the make and break connection mechanism of the wire block. 90

5. In a wire drawing machine, the combination with a driving means; of a shaft; a clutch mechanism therebetween whereby movement of the driving means is transmitted to said shaft; a drum actuated from 95 said shaft; a wire block; a clutch mechanism for actuating said wire block from said shaft; means for actuating the last mentioned clutch mechanism; and means for actuating the first mentioned clutch mechanism, said 100 latter means having such connection with the clutch mechanism associated with the wire block as to actuate the same when moving in one direction.

6. In a wire drawing machine, the combination with a driving means; of a rotating shaft; a make and break connection mechanism therebetween; a rotating drum positively driven from said shaft; a wire block; a make and break connection mechanism between said wire block and said shaft; a rock lever; a rod and link connection between said rock lever and the first of the above described make and break mechanisms; a rock lever having connection with 115 the make and break connection mechanism for said wire block; and an adjustable connection with the aforesaid rod and said latter rock lever, said connection being such that said rod may be moved in one direction without imparting movement to the rock lever. 120

7. In a wire drawing machine the combination with a driving means; of a rotating shaft; a clutch mechanism therebetween 125 whereby movement of the driving means is transmitted to said shaft; a drum actuated from said rotary shaft; a wire block; a clutch mechanism for actuating said wire block from said rotating shaft; a plurality 130

of levers, one of said levers being connected with the clutch mechanism associated with said wire block; means for connecting said levers with the first of said clutch mechanisms whereby movement thereof will actuate said clutch mechanisms, the connection with the last of said levers being such, however, that said lever receives movement only during the travel of said connection means in one direction.

8. In a wire drawing machine, the combination with a driving means; of a rotating shaft; a clutch mechanism therebetween whereby movement of the driving means is transmitted to said shaft; a drum actuated from said rotary shaft; a wire block; a clutch mechanism for actuating said wire block from said rotating shaft; a plurality of levers; a member for connecting said levers with each other; means for connecting said levers with the first of said clutch mechanisms whereby movement thereof will actuate said clutch mechanisms; a lever connected with the clutch mechanism associated with said wire block; and an extension device upon said member having a slidable connection with the last mentioned of said levers.

9. In a wire drawing machine, the combination with a driving means; of a rotating shaft; a clutch mechanism therebetween, whereby movement of the driving means is transmitted to said shaft; a drum actuated from said rotary shaft; a wire block; a clutch mechanism for actuating said wire block from said rotating shaft; a plurality of levers; a member for connecting said levers with each other; means for connecting said levers with the first of said clutch mechanisms whereby movement thereof will actuate said clutch mechanisms; a lever connected with the clutch mechanism associated with said wire block; an extension device upon said member having a slidable connection with the last mentioned of said levers; and means for varying the relative position of said extension device and said member.

10. In a wire drawing machine, the combination with a driving means; of a rotating shaft; a clutch mechanism therebetween whereby movement of the driving means is transmitted to said shaft; a drum actuated from said rotary shaft; a wire block; a clutch mechanism for actuating said wire block from said rotating shaft; a plurality of levers, one of said levers being connected with the clutch mechanism associated with said wire block; means for connecting said levers with the first of said clutch mechanisms whereby movement thereof will actuate

said clutch mechanism, the connection with the last of said levers being such, however, that said lever receives movement only during the travel of said connection means in one direction; and a slotted extension device upon said member having connection with the last mentioned of said levers by means of said slot.

11. In a wire drawing machine, a rotating drum; a rotating block; means for independently setting in motion said drum and said wire block through make and break mechanisms; and means for stopping the motion of said wire block while said drum is rotating.

12. In a wire drawing machine, a rotating drum; a rotating block; means for independently setting in motion said drum and said block through make and break mechanisms; mechanism for stopping the motion of said wire block having such relation to said means that it may be actuated independently thereof; and a locking device to prevent the premature actuation of said latter mechanism.

13. In a wire drawing machine, a rotating drum; a rotating block; means for independently setting in motion said drum and said block through make and break mechanisms; means, comprising in part a rock member, for independently stopping the motion of said block; and a locking device to prevent the premature movement of said rock member.

14. In a wire drawing machine, a rotating drum; a rotating block; means for independently setting in motion said drum and said block through make and break mechanisms; means, comprising in part a rock member, for stopping the motion of said block; a locking device to prevent the premature movement of said rock member; and means for releasing said locking mechanism connected with the mechanism for setting said rotary drum in motion.

15. In a wire drawing machine, a rotating drum, a rotating block; means for independently setting in motion said drum and said block through make and break mechanisms; means comprising in part a rock member, for stopping the motion of said block; a locking device to prevent the premature movement of said rock member; means for releasing said locking mechanism connected with the mechanism for setting said rotary drum in motion and adjustable thereto.

In testimony whereof, I have hereunto affixed my signature.

WILLIAM D. PIERSON.
